UNITED STATES PATENT OFFICE.

VINCENT JAKOB STERLING, OF BERLIN, CONNECTICUT.

CAP-VIZOR.

1,232,992.

Specification of Letters Patent. Patented July 10, 1917.

Application filed July 6, 1916. Serial No. 107,740.

To all whom it may concern:

Be it known that I, VINCENT JAKOB STERLING, a subject of the Emperor of Austria, and a resident of Berlin, in the county of 5 Hartford and State of Connecticut, have invented certain new and useful Improvements in Cap-Vizors, of which the following is a specification.

This invention relates to improvements in 10 wearing apparel, particularly head gear of the type known as caps, in contradistinction to hats which are provided with a brim extending around the lower edge.

The principal object of the invention is to 15 provide means combined with a cap which may be used as a vizor by proper adjustment, or removed at such times as may be desired, without in any way conflicting with the use and appearance of the cap.

20 A second object is to provide such vizors of transparent material through which light rays may pass in such manner as not to injure the eyes of the wearer.

These and other objects are attained by 25 the novel combination of parts hereafter described and shown in the accompanying drawing, in which:—

30 Figure 1 is a longitudinal sectional view, taken on the center line of a cap, showing the vizor attached.

Fig. 2 is a front elevation of the same.

Fig. 3 is a front plan view of the vizor.

Fig. 4 is an enlarged sectional view taken on line 4—4 of Fig. 3.

35 Fig. 5 is a similar sectional view taken on line 5—5 of Fig. 1, and

Fig. 6 is a sectional view taken on line 6—6 of Fig. 3.

The cap is here shown to have a cylindrical body 10, and integrally formed crown 11, the body being partially encompassed by a band 12 extending entirely around its circumference near the lower part thereof, as is usual with caps of this character.

40 Eyelets 14 for ventilating purposes are provided on both sides of the cap near the upper portion thereof.

Through both band and body of the cap are formed a plurality of minute perforations 15, to which is attached by stitching, rivets or the like, a partial band 16 formed of a single flat strip of resilient material bent, closely folded and formed with two lower portions 17 which inclose a circular 45 space 18, the edges 19 being turned slightly

out to receive the bulbously formed bead 20 of a strip 21 doubled upon itself and secured by rivets 23 or the like to the vizor 25 in such manner that upon bending the vizor arcuately, together with the strip 21, the beaded portion 20 may be entered within the space 18 and become engaged therein, so as to hold the vizor firmly in position.

The material of the vizor is preferably transparent, so that light rays may pass 65 therethrough, but sufficiently opaque to overcome any discomfort to the wearer when exposed to the direct beams of the sun. The outer edge of the vizor plate 25 may have secured to it a strengthening frame 26, the 70 whole being of semi-elliptic shape as clearly indicated in Fig. 3.

From the foregoing it will be seen that the attachment may be readily made at any desired moment, and that the vizor may be 75 detached with equal readiness. When not in use, the vizor may be carried in the pocket, it being very thin and light in its construction.

The cap is in nowise disfigured by the 80 attachment as will be clearly evident, and the expense of the same is very small.

Having thus described my invention, what I claim as new and desire to secure by Letters Patent, is:—

1. In a cap, the combination with the body 85 of a transparent vizor, a resilient arcuate strip permanently attached to the interior of said cap body on the lower front edge thereof, and a beaded strip suited to engage with said arcuate strip secured to said vizor, 90 whereby it may be connected or disconnected from said cap body.

2. In a cap, the combination with the body 95 thereof, of a spring band having a substantially circular cross-section and a longitudinal opening, said band being permanently engaged in the interior of said cap body on the lower edge thereof, an arcuate transparent vizor, a border attached to the edges of 100 said vizor, and a flexible strip having an enlarged beading at its upper edge secured to the upper portion of said vizor, said strip being engageable within said first strip, and adapted to be retained therein.

105 Signed at New Britain, in the county of Hartford, and State of Connecticut, this 23d day of May, A. D. 1916.

VINCENT JAKOB STERLING.
